BRUSH HOLDER

Paul B. Burrus, Dayton, Ohio, assignor to Richard A. Niekamp, doing business as American Aircraft Associates, Dayton, Ohio

Application July 13, 1943, Serial No. 494,549

4 Claims. (Cl. 171—324)

1

This invention relates to a brush holder for an electric motor or a generator and more particularly to the mounting and the adjustment thereof.

An object of this invention is to provide a brush holder that may be adjusted through any predetermined increment and rigidly secured in position as soon as it has been adjusted.

Another object of this invention is to provide a support for a brush holder that may be removed from the housing or from its supporting portion to remove the brush supported thereby without disturbing the other brushes.

Another object of this invention is to provide adjustable clamping means for securing a brush holder in any adjusted position upon a support that may or may not be mounted for oscillatory adjustment to change the angular relation of the brush with respect to the commutator segments.

Another object of this invention is to provide a support for a brush holder that is insulated from the frame of the electrical device and that is provided with means for compensating for changes in the dimensions of the insulating material.

Other objects and advantages reside in the construction of parts, the combination thereof and the mode of operation, as will become more apparent from the following description.

In the drawings,

Figure 1 discloses a brush mounting supporting a pair of brushes and attached to the end frame of a motor, which end frame, together with some of the mounting parts, has been shown in cross section.

Figure 2 discloses the brush holder and a portion of the support as viewed from one side, with the brush resting upon a commutator segment or slip ring, as the case may be.

Figure 3 is a side elevational view of the brush retaining stud or support as it appears before assembly.

Figure 4 is a side elevational view of a slotted bushing provided with a taper, used in securing the stud in position.

Figure 5 is a fragmentary exploded view of a part of the brush supporting assembly.

In the past, numerous types of brush holders have been developed and used on electric devices such as motors and dynamos or generators. These generally provide for adjustment of the brush with respect to the commutator, so as to properly position the brush and so as to permit adjustment of the brush to compensate for its wear.

2

The device disclosed herein provides for these adjustments by permitting the brush holder to be adjusted through any desired increment away from and towards the commutator and for oscillating the brush holder through any desired increment about a pivot parallel to the axis of rotation of the armature. Furthermore, the brush holder is secured in any adjusted position by clamping mechanism or locking mechanism that is dependable, efficient and easily constructed.

Referring to the drawings, the reference character 10 indicates a frame of an electric motor, dynamo or generator, as the case may be. An 15 armature, that has not been shown, is journaled in the frame 10 and is provided with a commutator 14, as is well known to those skilled in the art.

The end frame 10 is provided with an aperture 20 having a tapered portion 20, a shoulder 22, a cylindrical portion 24 and a rabbet 26. This aperture is used for insulatingly supporting a brush holder supporting member 30. This brush holder supporting member 30 has a hexagonal 25 portion 32 that may represent the cross sectional area of the original stock used in manufacturing this member. The hexagonal portion 32 may be used as a bolt head. One end of member 30 is turned in a lathe, or in any other suitable manner, so as to form a cylindrical portion 34 provided with threads 36. The opposite end is formed into a pentagonal cross sectional area forming a plurality of facets 38, that are used for attaching the brush holder, as will be described 30 more fully later.

The cylindrical portion 34 projects through the tapered portion of the aperture in end frame 10. This cylindrical portion 34 is surrounded by a cylindrical insulating sleeve 40 positioned within 40 a conical bushing 42, having a taper reversed to the taper of the tapered portion 20. The conical bushing 42 is provided with a longitudinal slot 43, permitting expansion and contraction thereof. The large end of the bushing 42 abuts a metallic 45 washer 44. The reduced end of the tapered bushing 42 terminates in spaced relation from the reduced end of the tapered portion 20 of the aperture in the end frame 10.

A copper contact member 50 is provided with 50 an aperture receiving the cylindrical portion 34. This contact member is provided with a reentrant portion 52 that grips a ring 60 used in connecting pairs of brushes of the same polarity together. Member 50 makes an electrical contact directly 55 to member 30. Member 50 is seated against a

metallic washer 62 abutting a shoulder found between the hexagonal portion 32 and the cylindrical portion 34 of member 30. A plurality of insulating discs or washers 70 are positioned between member 44 and member 50, so as to provide an insulating support for the assembly. An insulating washer 72 is mounted on the opposite end of the cylindrical portion 34 and is seated against a metallic washer 74 abutting a resilient disc-shaped metallic washer-like member known in the trade as a beville washer 76 engaging a washer 78, held in position by a lock washer 80 engaging a nut 82, tightened on the end of the cylindrical member 34, so as to hold the assembly in rigid position. In the event any of the members made of insulating material should expand or contract, this is compensated for by the disc-shaped washer member 76 exerting a tightening pressure in spite of the changed dimensions. A cup 90 is press-fitted or snapped into position and seated in the rabbet 26, so as to seal the nut 82 and the parts associated therewith.

In order to adjust the angular position of the brush with respect to the commutator 14, it is merely necessary to remove the cap 90 and loosen the nut 82 to permit rotation or oscillation of member 30 and the parts carried thereby. When the brushes have been adjusted into proper angular position, the nut 82 may be tightened and the cap 90 snapped into position.

The opposite end of member 30 may support one or more brush holders which will now be described. The brush holder may include member 100, having a U-shaped member 102 attached thereto, providing a channel for the brush 104 spring urged by a spring 106 mounted upon a lever 108 attached to a ratchet member 110, held in a tense position by a suitable spring 112 seated in one of the notches in ratchet member 110. This assembly is pivotally mounted on a pivot 114 journalled in an extension 116 projecting from substantially U-shaped channel member 118. The two legs or flanges 120 of the U-shaped channel member 118 are provided with apertures receiving bolts 122 passing through a cross bar 124 having a channel-shaped cross sectional area, as best seen in Figure 5. The channel-shaped cross bar 124 is provided with a pair of inclined surfaces 126 engaging similar surfaces on a clamping member 128 that is provided with a V-shaped notch or groove seated upon two sides of the pentagonal portion 36 of member 30. The inclined surfaces or side walls 126 have a wedging action when in engagement with the clamping member 128, so as to rigidly wedge clamping member 128 in home position. By loosening the screws or bolts 122, the brush holders may be adjusted in the direction of the arrow 150, shown in Figure 1, or in the opposite direction, so as to move the brush in a direction parallel to the axis of rotation of the armature.

The distance between the legs 120 is much greater than the distance across member 30 and the corresponding dimension of the clamping member 128. This permits adjustment of the brush holder either away from the commutator, in the direction of the arrow 152 shown in Figure 2, or towards the commutator when moving the brush holder in the direction opposite to the direction of the arrow 152. Thus, it is seen that the brush holder may be positioned in the proper angular relation with respect to the commutator, may be positioned in the proper axial position and it may be positioned in the proper radial position.

Although the preferred embodiment of the device has been described, it will be understood that within the purview of this invention various changes may be made in the form, details, proportion and arrangement of parts, the combination thereof and mode of operation, which generally stated consist in a device capable of carrying out the objects set forth, as disclosed and defined in the appended claims.

Having thus described my invention, I claim:

1. A brush supporting assembly for use in an electric machine, said assembly including a retaining member having a cylindrical portion terminating in a threaded end, a split tapered bushing member encircling the cylindrical portion for use in clamping the retaining member to the end frame of an electric machine, said retaining member being mounted in the end frame for rotary adjustment about the longitudinal axis of the retaining member, the opposite end of the retaining member being provided with a portion having a plurality of facets, a brush holder member having a flat surface subtended by a pair of legs spaced further apart than the thickness of the retaining member, said brush holder member having its flat surface contacting one of the facets for lateral adjustment parallel to the longitudinal axis of the retaining member and for transverse adjustment between the legs in a direction parallel to the plane of said flat surface so that the brush holder may be adjusted in a rotary direction by adjusting the retaining member in the end frame, in a lateral direction by adjusting the brush holder laterally on the retaining member in a direction parallel to the longitudinal axis thereof and in a transverse direction parallel to the flat surface of the brush holder, and means for clamping the brush holder in adjusted position upon the portion of the retaining member having the facets.
2. A brush supporting assembly for use in supporting a brush in fixed relation with respect to the end frame of an electric machine, said brush assembly including a retaining member mounted for rotary adjustment in the end frame of the electric machine, means for rigidly attaching the retaining member in adjusted position upon the end frame, one end of the retaining member being provided with a portion having a plurality of facets, a brush holder member having a flat surface subtended by a pair of legs spaced further apart than the thickness of the retaining member, the brush holder member having its flat surface adjustably positioned upon one of the facets for lateral adjustment in a direction parallel to the longitudinal axis of the retaining member and for transverse adjustment between the legs in a direction normal to the longitudinal axis of the retaining member, and means for clamping the brush holder in an adjusted position upon the portion of the member having facets.
3. A brush supporting assembly for use in supporting a brush in fixed relation with respect to the end frame of an electric machine, said brush assembly including a retaining member mounted for rotary adjustment in the end frame, means for rigidly attaching the retaining member in adjusted position upon the end frame of the electric machine, one end of the retaining member having a pentagonal cross sectional area, a brush holder member having a flat surface subtended by a pair of legs spaced further apart than the thickness of the retaining member, said brush holder member having its flat surface mounted in contact upon one of the facets for lateral adjustment parallel to the longitudinal axis of the retaining member

and for transverse adjustment between the legs in a direction normal to the longitudinal axis of the retaining member, clamping means having a V-groove, the sides of the V-groove engaging a pair of facets opposite the side of the pentagonal portion contacting the flat surface of the brush holder, and a cross bar mounted upon the legs of the brush holder member for holding the clamping member rigidly against the retaining member for holding the brush holder member in adjusted position with respect to the retaining member.

4. A brush supporting assembly for use in supporting a brush in fixed relation with respect to the end frame of an electric machine, said brush assembly including a retaining member, means for rigidly attaching the retaining member to the end frame of the machine, said retaining member including a hexagonal portion, a pentagonal portion projecting from the hexagonal portion, brush holder means, said brush holder means including a portion having a flat surface subtended by a pair of legs, the distance between the legs being greater than the thickness of the retaining member to permit adjustment of said means in a direction normal to the longitudinal axis of the retaining member, said means being adjustably mounted for movement in a direction parallel to

the longitudinal axis of the retaining member, said means including a channel-shaped cross bar the sides of the channel being inclined, and a clamping member mounted between the pentagonal portion and the cross bar, said clamping member having complementary inclined surfaces for clamping the brush holder upon the retaining member.

PAUL B. BURRUS.
